CLAIM

The ornamental design for a table, as shown and described.

DESCRIPTION

FIG. 1 is a front perspective view of a table showing one embodiment of our new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a front perspective view of a table showing another embodiment of our new design.

FIG. 8 is a front view thereof.

FIG. 9 is a rear view thereof.

FIG. 10 is a left view thereof.

FIG. 11 is a right view thereof; and,

FIG. 12 is a top view thereof.

The broken lines shown in the figures represent portions of the table that form no part of the claimed design.

(Continued)

The legs of the table is shown with a symbolic break in their length. The appearance of any portion of the article between the break lines forms no part of the claimed design.

1 Claim, 12 Drawing Sheets
